UNITED STATES PATENT OFFICE

ALFRED E. HEFFNER, OF SEATTLE, WASHINGTON

SIRUP-PUMP CLOSURE

Application filed February 28, 1928. Serial No. 257,717.

This invention relates to improvements in sirup dispensing pumps of that character used at soda fountains and has for its principal object to provide a cover, or closure, for the 5 end of the pump spout whereby flies or other insects will be prevented from entering the spout while the pump is not in use, and which also serves to prevent dripping from the spout after use.

10 It is also an object of the invention to provide a closure device as above stated, having means for yieldably retaining it in closed position and with an opening means adapted to be engaged and moved by the rim of a 15 glass, or the like, when the latter is placed in position to receive sirup from the pump, to thereby move the closure to open position out of the way of the discharged sirup.

It is also an object of the invention to provide a device of the above character that may be easily attached to the spouts of sirup pumps as they are now constructed and without requiring any change or alteration in the design of the spout.

25 A still further object is to provide devices of the above character that are relatively inexpensive, which may be easily attached and which are automatic in their opening and closing action.

30 In accomplishing these and other objects of the invention, I have provided the improved details of construction, the preferred forms of which are illustrated in the accompanying drawings, wherein—

35 Figure 1 is a perspective view, showing a part of a soda fountain sirup pump with the pump spout equipped with a closure device embodied by the present invention.

Figure 2 is a sectional detail of the device 40 as applied to the spout of the pump; the closure element being shown in closed position.

Figure 3 is a similar view, illustrating the movement of the device to open position.

45 Figure 4 is a perspective view illustrating

an alternative means for attaching the device to the pump spout.

Referring more in detail to the drawings—

1 designates, in its entirety, what may be a sirup pump of a type now in general use 50 at soda fountains for dispensing the flavoring sirups. This pump is applied to the sirup container 2 and is of such construction that, by downward action of a yieldably mounted plunger 3, sirup will be forced from 55 the container through the pump discharge spout 4. As a general rule, the spouts of such pumps are uncovered at their ends and, unless they are guarded in some way, it is very difficult to keep flies or other insects from entering; this being especially true when the pump stands unused over night. Therefore, it is for the purpose of rendering such pumps 60 more sanitary and also for the purpose of catching any drip from the spout that the 65 present devices are applied.

In its preferred form of construction, the device consists of a housing made from a single piece of sheet metal and bent to provide a flat base portion 5 of about one-fourth inch 70 in width and approximately two inches long, from the side edges of which there extends the laterally turned, parallel side plates 6—6. This housing is secured to the spout, lengthwise thereof and at its under side near the 75 discharge end, by means of one or more short screws 7 which are projected upwardly through the base portion of the housing and threaded into the spouts.

Pivottally mounted within the housing, 80 near its upper end, by means of a pivot pin 8 that extends through the side plates 6—6, is a closure device for the end of the spout. This device is of bell crank form, provided with an arm 10 extended to a position beneath 85 the discharge opening of the spout and provided with an enlarged, downwardly cupped plate 11 that is adapted to fit tightly against the end of the spout. The other arm, 12, of the device extends downwardly from the pivot 90

point and is connected, by a pin 13, with one end of a link 14 which extends toward the other end of the housing where it is pivotally attached, by a pin 15, to the arm 16 of an opening lever 17. This lever 17 is also of bell crank form and is pivotally mounted between the plates 6-6 on a pivot pin 20, with the arm 16 extended upwardly from the pivot and the lever 17 extended forwardly 10 from the housing to a position beneath the end of the spout, as shown in Figure 2. A spring 21 is mounted on a pin 22 in the housing and this bears against the arm 16 to yieldably retain the closure member against the end of the spout.

15 In using the device, the rim of the glass or receptacle into which the sirup is to be discharged, as designated at 25 in Figure 3, is pressed upwardly against the end of the lever 17 and this actuates the parts to swing the closure device to open position, as illustrated in Figure 3, at which position it will be entirely removed from the path of the sirup discharged from the spout. By releasing the 20 pressure against the lever 17, the spring 21 actuates the parts to closed position.

25 In Figure 4, I have illustrated an alternative means for attaching such devices to the spouts. This comprises a clip 28 that is attached to the housing and which has paired fingers 29-29' adapted to embrace the opposite sides of the spout to hold the device in position.

30 Devices of this character may be readily applied to spouts of sirup pumps without requiring any change in the latter and will serve to retain the spouts closed at all times except when sirup is being discharged and, in this way, they will positively prevent 35 flies or other insects from entering the spout during periods of time when the pump is not in use and will also catch any drip that might otherwise flow from the spout after use. The devices are also automatic in their closing or 40 opening action and it is not necessary for an operator to manually actuate the device to open position when sirup is to be discharged; it being only necessary to press upwardly 45 against the arm 17 which, through the linkage provided, swings the closure to open position. This automatically closes when the 50 glass is removed.

55 Having thus described my invention, what I claim as new therein and desire to secure by Letters Patent, is:

60 A device of the character described, comprising a housing formed with a base portion and spaced side portions and means extended through the base for attaching the 65 housing to a discharge spout or the like, a member of bell crank form pivotally mounted in the housing and having a closure member at the end of one arm adapted to close against the discharge end of the spout, an actuating 70 lever of bell crank form pivotally mounted

in the housing, a link connecting an arm of the actuating lever with the other arm of the closure member, a spring bearing against the actuating lever to normally retain the closure in closed position; said actuating lever having its lower arm extended to a position below the end of the discharge spout at which it may be actuated by a receptacle placed in position to receive the discharge from the spout.

75 Signed at Seattle, Washington this 31st day of January 1928.

ALFRED E. HEFFNER.
